US0D1024256S

(12) **United States Design Patent** (10) Patent No.: **US D1,024,256 S**
(45) Date of Patent: ** Apr. 23, 2024

(54) **RIFLE**

(71) Applicant: **ERRESSE S.R.L.**, Brescia (IT)

(72) Inventor: **Rino Chiappa**, Brescia (IT)

(73) Assignee: **ERRESSE S.R.L.**, Brescia (IT)

(**) Term: **15 Years**

(21) Appl. No.: **35/515,828**

(22) Filed: **Dec. 5, 2022**

(80) **Hague Agreement Data**

Int. Filing Date: **Dec. 5, 2022**

Int. Reg. No.: **DM/225507**

Int. Reg. Date: **Dec. 5, 2022**

Int. Reg. Pub. Date: **Dec. 23, 2022**

(51) **LOC (14) Cl.** **22-01**

(52) **U.S. Cl.**

USPC **D22/108**

(58) **Field of Classification Search**

USPC D21/572, 573; D22/103, 108, 109, 199

CPC F41A 19/40; F41C 7/02; F41C 7/06
